UNITED STATES PATENT OFFICE.

JOHN WILLIAM HARTLEY, OF STONE, ENGLAND.

SEWAGE DISTRIBUTOR.

Application filed August 27, 1926, Serial No. 132,010, and in Great Britain August 29, 1925.

This invention relates to an improved rotary apparatus for distributing sewage upon circular filter beds, and consists in an apparatus substantially as hereinafter described and illustrated and as claimed in the appended claims.

In the drawings:—

Figure 1 is a side elevation of the apparatus, the bed and surrounding wall being shown in section, and broken away at the bottom.

Figure 2 is a plan corresponding to Figure 1 only part of the bed and surrounding wall being shown.

15 Figure 3 is an enlarged sectional elevation of one of the spraying nozzles.

Figures 4 and 5 are sectional elevations of the water wheel, showing the driving jet of sewage under different heads, and 20 means for directing the jet on to the wheel at certain heads.

Figures 6, 7 and 8 are respectively an elevation, plan and end elevation of the water wheel, and parts connected therewith.

25 Figures 9 and 10 are a plan and end elevation respectively of the water wheel and one means for transmitting power therefrom to the runner wheels by which the apparatus is driven.

30 Figure 11 is a sectional elevation of one form of central supporting column for the apparatus.

Referring to the drawings 1 is a central supporting column to which the sewage to be distributed is supplied. The sewage rises 35 up this central column 1 and passes thence along two tubular or pipe arms 2 and 3 which extend one from each side of the central column, and are in alignment. The 40 pipe arm 2 only is formed as a sprayed jet distributing arm, that is to say it is provided in the side with a series of holes fitted with nozzles 4 carrying spreading plates 5, the nozzles 4 having cleaning openings 6 closed 45 by removable stoppers or corks 7. The pipe arm 2 carries at its outer end a weight 8 which balances the weight of a water wheel 9 arranged at the outer end of the other arm 3. The sewage supplied through the column 1 to the arm 3 passes thence to the water 50 wheel 9. The sewage is discharged from the arm 3 on to the water wheel 9 through nozzles 10 in the form of spouts or jets 11 (Figures 4 and 5). The jets 11 rise to greater 55 or less heights according to the head of sewage in the column 1. In order to prevent the

jets 11 from being projected beyond the water wheel 9 without operating the wheel 9 when the head of sewage is comparatively great, a curved deflecting plate 12 is provided. Thus under the greater heads of sewage the jet 11 strikes the curved deflecting plate 12 at a point 13 as shown in Figure 4 whence it is deflected into the upper buckets 14 of the water wheel 9 by way of 60 cross vanes 15. The sewage jets 16, 17 produced at lower heads (Figure 5) are guided into the buckets 14 of the wheel 9 by cross vanes 18. At the lowest head, the jet passes directly over the lip or flange 19 into the 70 buckets 14 of the water wheel 9. The cross vanes 15 and 18 are supported from the flanged sides 20 of the deflecting plate 12. By providing an inspection opening 21 in the plate 12 the sewage jets may be viewed 75 through the opening. The sewage falls from the water wheel 9 directly upon the bed 22. The wheel 9 needs therefore to be clear of the bed 22 only by the necessary minimum clearance so that a very small head of sewage delivered at 23 into the lower buckets 80 14 of the water wheel 9 will rotate it.

The distributing arm 2 may be, if desired, shorter than the arm 3 by an amount corresponding to the width of the water wheel. 85 The water wheel 9 is utilized to rotate the apparatus as hereinafter described.

Any suitable means are provided to ensure that sewage is conveyed from the central column 1 to the pipe arm 3 before it is conveyed to the distributing arm 2 so that the water wheel 9 is set in motion and the apparatus begins to rotate before any discharge from the distributor arm commences.

Thus there is no dribbling of sewage while 95 the arms are stationary, and dosing chambers are rendered unnecessary.

As shown these means embody a fence or weir 24 in the central column 1. The same object may, however, be readily attained by 100 making the delivery outlet to the distributing pipe 2 at a higher level than that of the pipe 3.

Sewage is discharged at suitable intervals from the pipe arm 2 in the form of sprayed 105 jets produced by the spraying nozzles 4, provided with reflector or spreading plates 5, disposed at suitable distances apart along the pipe, the jets being with advantage of comparatively large cross section.

These jets extend and distribute sewage 110 over the bed 22 from a point 26 near the

centre to a point 27 near the periphery. The water wheel 9 distributes sewage over the surface of bed 22 from the point 27 to the surrounding wall 28 of the bed 22. Thus the bed 22 receives a dose of sewage covering its whole surface at each rotation of the distributing apparatus. The water wheel 9 is mounted on a horizontal shaft 29 (Figures 6, 7 and 8) which is preferably supported in closed end bearings 30 upon a frame 31. The frame 31 is mounted on the arm 3 by any suitable support and is fixed in position on the arm 3 as illustrated. The axis of the shaft 29 is radial to the central column and a runner or motor wheel 32 is fixed upon said shaft 29.

The runner or motor wheel 32 is made of any suitable size or width according to the nature of the track 33 available. The wheel 32 may be of cast iron with a vulcanized rubber tyre or a grooved wheel with an air inflated tyre, or iron, steel, or the like, as will be readily understood by those skilled in the art and therefore not requiring illustration. It is preferred to employ a vulcanized rubber tyred motor or runner wheel when the invention is to be applied to existing distributing apparatus. The motor wheel 32 travels along the outer circular wall 33 (Figures 1 and 2) which almost invariably encloses and surrounds the bed 22 of existing distributors, or may be built up of brick, stone, concrete or the like partially embedded in the media as near to the periphery of the bed H as possible or convenient.

Figures 9 and 10 indicate one mode of rotating the distributor when the surrounding wall 33 is considerably raised above the surface of the bed 22.

Referring to these figures it will be seen that on the shaft 29 is keyed a sprocket wheel 34, which, by means of a chain 35, drives a sprocket wheel 36 on the shaft 37 of the motor or runner wheel 32.

The motor or runner wheel 32 is mounted in suitable bearings on supporting stands 38 carried by the frame 39, and bears on the wall 33. The water wheel 9 thus drives the distributor, from its lower level, the motor wheel 32 travelling on the top of the raised outer wall 33. As the distributor is propelled by the water wheel 32 from the arm 3 any known form of dashplate or nozzle may be used for spreading the jets of sewage as they leave the distributing arm 2. As the bulk of the sewage is discharged from only one distributing pipe arm proper, namely, the arm 2 the jets may be much larger and fewer in number than it is now possible to use without sacrificing efficiency, on any existing pipe arm distributor where the weight is wholly or in part borne upon the central column. With only one distributing arm proper one arm only requires to be cleaned and this also with less frequency

as the nozzles for the issuing jets are of much greater area than those of existing distributors.

Substantially the whole weight of the arms 2 and 3 may be supported together with the balance weight 8 and the water wheel 9 upon the central column 1 by the usual wire rope stays as shown in Figure 1 the water wheel 9 being made heavier than the balance weight by an amount sufficient to ensure that the wheel 32 bears upon the wall 33 with only so much weight as is necessary to enable the wheel 32 to rotate the distributor by its friction upon wall 33. The wear of the wheel 32 is thus reduced.

Referring now to Figure 11, which is a sectional elevation of a suitable form of central column, it will be seen that this column embodies an inner fixed tube 40 and a surrounding outer rotary casing 41 provided with flanged branches 42 for attachment of the pipe arms 2 and 3.

The inner tube 40 is provided with ports or openings 43 through which the sewage rising in the tube 40 passes to the outer casing 41 for delivery, by way of the branches 42, to the pipe arms 2 and 3, the fence 24 being provided on the apparatus to ensure delivery of the sewage to the pipe arm 3 before delivery to pipe arm 2 for the purpose previously set forth.

In order to enable the sewage to be retained in the space 44 between the tube 40 and the casing 41, the casing 41 and the tube 40 are connected by means of a flexible tube 45 of leather, canvas or the like of suitable diameter and length. The upper end of this tube 45 is attached to the lower extremity of the outer tube 41 and its lower end is attached to a sleeve 46 which fits closely against the inner tube 40 and is provided with water grooves 47 on the inside.

A suitable projecting flange 48 is provided on the upper end of the sleeve 46 to facilitate attachment of the flexible tube 45 thereto. By thus making a close fit between the tubes 40 and 41 by means of the sleeve 46 the sewage is retained in the space 44.

Alternatively a stuffing box now in general use may be employed as will readily be appreciated by those skilled in the art without requiring illustration. The sleeve is however preferred in that it is free from the objection incidental to such stuffing boxes namely that the packing of a stuffing box when injudiciously screwed up, wears and damages the central fixed tube 40.

Although a water wheel has been referred to throughout the specification, this may be replaced by a water turbine if preferred.

I claim:—

1. In a rotary pipe arm sewage distributor a sewage-driven water wheel for rotating the pipe arms, a nozzle through which the sewage utilized to actuate said water wheel is

sues in the form of a jet, substantially tangential to said water wheel and a deflector for directing said sewage jet on to said water wheel when the sewage for actuating said water wheel is supplied under greater heads, whereby the distributor is capable of effective operation under varying pressure heads.

2. In a rotary pipe arm sewage distributor, a sewage-driven water wheel composed of a series of vaned wheels on a common shaft, nozzles through which the sewage utilized to actuate said water wheel is constrained to issue in the form of jets, substantially tangential to said vaned wheels and deflectors for directing said sewage jets on to said vaned wheels when the sewage for actuating said vaned wheels is supplied under heads of a higher order, said deflectors being provided with inspection windows for inspecting said jets.

3. Apparatus for distributing sewage over a circular filter bed, comprising a central supporting column, a pair of oppositely arranged hollow radial arms supported mainly by said column, one of said arms being fitted 25 at its outer end with a water-wheel distributor having a driving wheel engaging with a circular track surrounding said bed, the other of said arms having nozzles and spreading means and adapted to balance substantially the first mentioned arm and water-wheel distributor whereby only sufficient weight need come on the track to insure efficient driving, said central column being adapted to supply sewage to said arms for 30 the distribution by the nozzles of the one and by the water-wheel distributor of the other.

In testimony whereof I have signed my name to this specification.

JOHN WILLIAM HARTLEY.
